SKI BRAKE

Harry Wesley Varner, Prince Rupert, British Columbia, Canada

Application August 25, 1941, Serial No. 408,240

1 Claim. (Cl. 280—11.13)

The present invention relates to new and useful improvements in brake attachments for skis.

An important object of the invention is to provide an attachment for a ski which will act as a brake to prevent the wearer of the skis from sliding backward when climbing hills.

Another object of the invention resides in the provision of a novel means for retaining the attachment in inoperative position when gliding forward on the skis.

The invention also consists in certain other features of construction and in the combination and arrangement of the several parts, to be hereinafter fully described, illustrated in the accompanying drawing and specifically pointed out in the appended claim.

In describing my invention in detail, reference will be had to the accompanying drawing wherein like characters denote like or corresponding parts throughout the several views, and in which in the drawing:

Figure 1 is a side elevational view of a ski showing the improved attachment applied thereto.

Figure 2 is an enlarged top plan view of the rear end portion of the blade of the ski showing the brake attachment in inoperative position.

Figure 3 is a longitudinal sectional view taken substantially on line 3—3 of Figure 2.

Figure 4 is a fragmentary side elevational view of the ski and illustrating the position of the attachment in use.

Difficulty is sometimes experienced by the wearers of skis when ascending an incline or hill due to the tendency of the skis to slide rearwardly. The present invention has been designed to prevent this rearward sliding movement as the wearer ascends an incline or hill.

Referring to the drawing for a more detailed description thereof, a ski of conventional construction is generally designated by the reference numeral 5, the forward end of which inclines upwardly as indicated at 6 while the rearward end 7 is relatively flat. The ski further includes a means 8 for securely attaching the shoe 9 of the wearer in a manner to assure safety in use.

The brake attachment, in accordance with the present invention, is generally designated in the several views by the reference numeral 10 and includes an elongated member 11 formed of metal or other suitable material that is attached by means of screws, or similar fasteners 12, to the top surface of the rear end of the ski 5. As best shown in Figure 3 of the drawing, the member

11 projects slightly beyond the rear edge of the ski and is formed with a looped tab 13 adapted to receive a hinge pin 14.

5 A substantially rectangular shaped plate 15 is hingedly secured to the member 11, one edge of said plate being formed with spaced looped tabs 16 which align with the looped tab 13, a pin 14 being disposed through the tabs 13 and 16 respectively, for hingedly mounting the plate to the ski. By this construction, the plate 15 is free to swing on its hinge to assume a position at substantially right angles to the ski as shown in Figure 4 of the drawing as the wearer ascends an incline or hill. In this position, the plate will 10 become imbedded in the snow thereby precluding rearward sliding movement. As the ski is lifted by the wearer during walking movement, the plate 15 will, of course, be raised from the snow and may be caused to assume a substantially horizontal position due to its loose hinge connection.

15 If desired, the rear edge of the ski may be provided with spaced pins 17, against which the plate abuts when in a substantially vertical position, said pins aiding in eliminating the packing of snow between the plate and the ski.

20 In accordance with the present invention, additional means have been provided for retaining the plate 15 in the inoperative position shown in Figures 2 and 3 of the drawing, in which position said plate will be resting in a plane parallel to the top surface of the ski and the member 11. This means comprises a coil spring 18, the looped mid portion 19 thereof extending forwardly toward the rear end of the ski. The coil spring 18 is formed of a single length of wire, the ends 20 of which are retained beneath the member 11 and after formation of the coil 18 said ends 25 extend forwardly substantially parallel as clearly shown in Figure 2 of the drawing. The mid portion 19 is raised against the tension of the coil spring 18 for releasing the plate 15 from the position shown in Figures 2 and 3. As is to be understood, with the parallel portions 21 of the coil spring 18 resting against the plate 15, said plate will be securely locked in an inoperative position.

30 The edge 22 of the plate 15 is pointed and preferably curves downwardly and inwardly for engagement with the snow or ice and to become imbedded therein to thereby prevent rearward slipping of the ski when ascending a grade.

35 With the brake plate 15 in the inoperative position shown in Figures 2 and 3, normal use of

the ski in descending an incline or slope is readily possible. It is only when ascending an incline or hill that the brake plate is released from its inoperative position.

Also it will be understood, of course, by those skilled in the art that variations in the hereinabove described device involving the substitution of substantial equivalents for the devices described are intended to be comprehended within the spirit of the present invention and that the invention is capable of extended application and is not confined to the exact showing of the drawing nor to the precise construction described and, therefore, such changes and modifications may be made therein as do not affect the spirit

of the invention nor exceed the scope thereof as expressed in the appended claim.

What is claimed is:

5 A brake attachment for skis, comprising an elongated member secured to the top face of a ski and provided with a looped tab beyond the rear edge of the ski, a plate hingedly attached to said tab and adapted to be disposed at right angles to said member when braking said ski,
10 and a coil spring having its free ends clamped to the face of the ski by the elongated member and provided with a looped intermediate portion engaging the plate for holding it in an inoperative position on the ski.
